United States Patent

Des. 241,267
Patented Aug. 31, 1976

241,267

ELECTRONIC CASH REGISTER OR SIMILAR ARTICLE

William L. King, 2274 Yorkshire Place, Dayton, Ohio
45419, and Thomas L. Hermann, 4540 Selma Pike,
Springfield, Ohio 45502

Filed Dec. 20, 1974, Ser. No. 534 938

Term of patent 14 years

Int. Cl. D20—02

U.S. Cl. D52—4 A

FIG. 1

FIG. 2

FIG. 3

FIG. 4

FIG. 5FIG. 1 is a left, front, perspective view of an electronic cash register or similar article, mounted on a cash drawer, showing our new design;

FIG. 2 is a right, front, perspective view thereof;

FIG. 3 is a right, side, elevational view thereof;

FIG. 4 is a left, side, elevational view thereof;

FIG. 5 is a rear elevational view thereof; and

FIG. 6 is a left front perspective view of another embodiment of our new design of FIG. 1 wherein the cash drawer has been eliminated.

We claim:

The ornamental design for an electronic cash register or similar article, as shown and described.
